POWER DRIVEN TOOL

William Harry Ray, Chicago, Ill.

Application April 29, 1931, Serial No. 533,621

6 Claims. (Cl. 144—32)

This invention relates to machinery for inserting or driving screws into wood or metal or other materials.

Generally stated, the object of the invention is to provide a novel and improved construction and arrangement whereby the mechanism for rotating or turning or driving the screw is adapted to do the work without danger of overdriving the screw or turning the screw after it is fully inserted, and whereby the screw driver point is normally at rest while the motor-driven connections for operating the screw driver point are continually rotating.

Another object is to provide a novel and improved construction of feed mechanism for automatically feeding the screws into position to be driven or inserted.

Another object is to provide a novel and improved construction of counterbalance for effectively counterbalancing the screw-inserting mechanism, which latter is movable up and down at will by the operator or user of the machine.

It is also an object to provide certain details and features of construction tending to increase the general efficiency and the desirability of a screw driving or inserting machine of this particular character.

To the foregoing and other useful ends, the invention consists in matters hereinafter set forth and claimed and shown in the accompanying drawings, in which—

Fig. 1 is a side elevation of a screw-inserting machine embodying the principles of the invention;

Fig. 2 is an enlarged vertical section of the counterbalancing mechanism for supporting the power-operated screw-inserting or driving elements for up and down movement;

Fig. 3 is a vertical section on line 3—3 in Fig. 4, showing the automatic hopper mechanism for feeding the screws;

Fig. 4 is a horizontal section on line 4—4 in Fig. 3 of the drawings;

Fig. 5 is a horizontal section on line 5—5 in Fig. 45 3 of the drawings;

Fig. 6 is an enlarged detail section on line 6—6 in Fig. 3;

Fig. 7 is an enlarged detail section on line 7—7 in Fig. 3;

Fig. 8 is an enlarged detail section on line 8—8 in Fig. 3;

Fig. 9 is an enlarged vertical section of the motor-driven elements and casing therefor, for rotating the screw driver point or tool;

Fig. 10 is an enlarged vertical section of a por-

tion of the feed mechanism for feeding the screws; Fig. 11 is a detail section on line 11—11 in Fig. 10 of the drawings;

Fig. 12 is a detail sectional view of one of the parts;

Fig. 13 is an underneath plan view of the part shown in Fig. 12;

Fig. 14 is a plan view of one of the parts;

Fig. 15 is a sectional view of the part shown in Fig. 14;

Fig. 16 is a section on line 16—16 in Fig. 9;

Fig. 17 is a section on line 17—17 in Fig. 9.

As thus illustrated, the invention comprises a bracket arm 1, which supports the motor and gearing housing 2 of the tool-operating mechanism, and which is in turn supported on a vertical tube 3 that is telescoped in a larger tube 4 and held in adjusted position therein by the collar and screw 5 shown for this purpose. In this way the arm 1 and the motor 2 can be adjusted up and down. The tube 4 is slideable up and down in the bearing 6 in the upper portion of the separable housing 7, and in the bearing 8 at the bottom of this housing, a spline 9 preventing the tube from rotating in these bearings. The lower end of the tube 4 is connected by a rod 10 with the foot-pedal 11, so that the bracket and the housing and tool can be pulled downward to drive or insert the screws. A spring 12, applied as shown, normally pulls upwardly on the rod 10, and thus keeps the bracket 1 and the housing 2 in elevated position. The weight of the bracket 1 and the housing 2 is counterbalanced by the weight 13, which is movable up and down in the housing 7, this weight being carried on a cable 14 that extends over the sheaves 15 in the upper portion of the housing 7, and then under the sheave 16 carried by the tube 4, whereby the weight of the tube 4 on the sheaves is equalized, so that the end portions of the cable 14 are equalized in their pull on the weight 13 of the counterbalancing mechanism. In this way, the weight 13 is not liable to be skewed or tilted in a manner that would cause it to bind on the tube or on the inner surface of the casing or housing in which it is enclosed.

The motor 17, of any suitable character, is provided with a pinion 18 that engages the gear 19 on the upper end of the member 20, which latter is hollow and enclosed by the tubular or cylindrical casing 21, which has its upper end removably screwed into the lower portion of the housing 2, previously mentioned. The screw driver point or tool 22 has a shank 23, terminating

in the chuck shown, the latter having an upper portion 24, mounted vertically to rotate in the ball bearings 25 and 26, suitably held in the lower portion of the cylindrical housing 21, previously mentioned. The shank portion 24 has its upper end provided with a clutch member 27, and with a spring-supported ball member 28, as shown. The upper clutch member 29 is mounted on the lower end of the stem 30, which latter has a flat head portion 31, as shown. The under side of this head portion 31 is provided with ball cavities 32, as shown. The ring member 33 is provided with spline projections 34 for engagement with the spline grooves 35 on the inner side of the member 20, and with ball sockets 36 on both sides thereof, so that it can be turned over when it becomes worn on one side. The balls 37,—say, three in number,—are disposed between the cavities 32 and the cavities 36, and are rigidly held in member 31, as shown. These balls can jump from cavity to cavity, in ring member 33, when the screw is fully inserted, and when it is desired to stop the rotation of the screw driver tool 22, previously mentioned. An ordinary ball thrust bearing 38 is interposed between the top of the head 31 and the member 20, as shown. The ring or bushing 39 is loose on the stem 30, and the coil spring 40 is interposed between this ring 39 and the ring 33, previously mentioned. On its bottom, the ring 39 is provided with three ball cavities 41, in which the balls are rigidly held, as shown, and the screw plug 42, which is screwed into the lower end of the member 20, is provided with shallow ball cavities 43 to engage the balls 44, three in number, whereby these balls can jump from cavity to cavity when the plug 42 is screwed up or down to vary the tension of the spring 40 in a manner that will be readily understood. The ring 39 has spline plugs 45 that engage the spline grooves 35, previously mentioned. As shown, the upper clutch member 29 has a central portion 46 for engagement with the ball element 28, whereby the clutch is normally held open by the spring 47 in the lower clutch member. When the tool 22 is moved upward, the clutch is closed, and power is communicated to the tool for rotating the screw. When the screw is fully inserted, the spindle 30 will cease to rotate as the balls 37 will slip or jump from cavity to cavity, in ring member 33, and thus prevent further rotation of the screw driver tool.

Means are provided for automatically feeding the screws as follows: A hopper 48 is provided on the bracket arm 1, previously mentioned, and is provided with a rotary cylinder 49 which oscillates back and forth about a horizontal axis. The horizontal shaft 50 of said hopper mechanism has a pinion 51 that engages the vertical rack 52, as shown, said rack being mounted in stationary position on the base or table 53 of the machine. When the treadle 11 is operated, the hopper mechanism moves up and down, and the rack and pinion serve to rotate the cylinder 49, first one way and then the other. Inside of the cylinder 49, rigid with the interior thereof, are radial blades 54, which are rigid with the outer cylindrical wall of the cylinder. The cylinder is mounted on the shaft 50, as shown, being made in two sections, one section having the hub 55, and the other section having the hub 56, telescoped within the other hub, as shown. The cylinder section 57 is held against the pinion 51 by a collar 58, pinned on the shaft 50, previously mentioned. The cylinder section 59 is held on said shaft, and

keyed thereto, by the pivoted spring-pressed key device 60, which is mounted on the outer hub 61 of this cylinder section, and which engages the outer portion of the shaft, whereby the shaft rotates the cylinder section 59, but does not rotate the cylinder section 57, to which latter the hopper 48 is united. The brushes 62 are on the hub 55, which latter is separate and adjustable, and hence these brushes rotate in the cylinder section 57, back and forth, in the desired manner, when the tube 3 is moved up and down. As shown, the cylinder section 57 has a side opening 63, which communicates with the hopper 48, in which latter are placed the screws. Also, the lower side of the cylinder section 57 has a feed slot 64 therein, for the screws, with a bevel guide 65 at one side thereof, this slot 64 having its end portions out of line with each other, as shown in Fig. 5 of the drawings. The feed tube 66 communicates with the guide slot 64, being provided at its end with a slot 67, as shown, through which the brushes 62 may enter to sweep the screws into the tube. The lower side of the tube 66 has a slot 68 in which the screws slide downwardly, as shown. If a screw does not enter the tube 66 in the right manner, or tries to enter head first, the brushes 62 will sweep it back again when the rotation is reversed, and in this way the proper feed of the screws is insured.

The feed tube 66 communicates with the upper end of a vertically disposed feed tube 69, as shown in Fig. 10 of the drawings, through which the screws drop vertically onto the pivoted escapement element 70, upon which latter each screw is caught by its head. The nozzle 71 and the feed tube 72 are movable up and down slightly, the nozzle being slideable up and down on the screw driver tool 22, in order that the latter may come down and engage a screw, and then move upwardly relatively to permit the escape of another screw from the passage 73 into the nozzle 71, as shown. The rod 74 is rigid with the nozzle 71, and slides up and down in the bracket 75, which is rigid with the tube 69 and with the cylindrical casing 21 previously mentioned. A spring 76 is provided on said rod 74, serving normally to keep the nozzle 71 down on the shoulder 77 of the screw driver tool 22, in the manner shown in Fig. 10 of the drawings. The rod 74 has a cam portion 78 for operating the escapement 70, whereby the up and down movement of this rod will cause the escapement 70 to release the screws, one by one, into the passage 73 below. It will be understood that the nozzle 71 slides up on the screw driver tool 22, when the lower end of the nozzle is brought down on the work, and then slides down again when the driving mechanism is lifted upward. In order that the screws may be released from the nozzle, the sides of the latter are provided with springs 79 having their lower ends provided with supporting portions 80 for supporting the screw heads in position to be engaged by the screw driver tool 22, as shown more clearly in Fig. 11 of the drawings. When the screw is driven home, its head will spread the portions 80 apart, and this permits the screw to be fully inserted. The springs 79 will then bring the portions 80 into normal position to catch and support the next screw.

The member 33 serves as a tension disk having shallow depressions on both sides to permit the disk to be turned over and used on the other side. Again, it will be seen that the member 39 is in the nature of a floating bearing containing steel balls held rigidly in place to lock the tension ad-

justment. In addition, the member 40 constitutes a single spring to apply tension to the members 33 and 39 to control the tension while the screw is being driven and to lock the adjustment. As to the member 42, it will be seen that the tension adjusting nut thus provided has a series of shallow depressions to engage the steel balls held in the member 39, as shown in the drawings. There is a tension disk, as shown, for the balls which are held in the member 31 to prevent them from losing their positions in relation to each other. The balls must be equally spaced, for otherwise the tension would not be effective.

As shown, the brushes 62 are attached to an adjustable ring, which latter is desirable to obtain correct operation. As to the slot 67, it will be seen that it is important to properly feed the screws and to clear the opening of screws that do not enter correctly, such improperly entering screws being swept back by the brushes, as previously stated. The cylinder section 59, and also the vanes 54, are important and serve in the manner described to insure proper feeding of the screws. It will be seen that the bevel guide 65 is in the nature of a deflecting shoe, for the purpose stated, and is an important feature of the invention. Again, the invention obviously involves the combination of an oscillatory hopper and reciprocating driving means.

What I claim as my invention is:

1. In apparatus for rotating a tool by power, the combination of a rotary member for supporting the tool in position to perform its desired work, a housing enclosing power controlling and transmission devices for rotating said member, a fixed table for the work, supporting and guiding instrumentalities mounted on said table at one side of said tool and whereby said housing is movable vertically to cause axial movement of said tool, means on said instrumentalities to adjust the housing and thereby move the tool up and down, said devices having means operable by said axial movement to open and close the mechanical transmission of power to said tool, and a motor rigid with said housing for operating said devices, movable up and down bodily therewith, said housing and motor being automatically movable upwardly in fixed relation, thereby to release the tool from the work and automatically open said transmission, said tool being a screwdriver, in combination with automatic mechanism for automatically feeding screws to the screwdriver, movable up and down bodily with said motor, with fixed means on said table to operate said mechanism.

2. In apparatus for rotating a tool by power, the combination of a rotary member for supporting the tool in position to perform its desired work, a housing enclosing power controlling and transmission devices for rotating said member, a fixed table for the work, supporting and guiding instrumentalities mounted on said table at one side of said tool and whereby said housing is movable vertically to cause axial movement of said tool, means on said instrumentalities to adjust the housing and thereby move the tool up and down, said devices having means operable by said axial movement to open and close the mechanical transmission of power to said tool, and a motor rigid with said housing for operating said devices, movable up and down bodily therewith, said housing and motor being automatically movable upwardly in fixed relation, thereby to release the tool from the work and automatically open said transmission, said tool being a screw-

driver, in combination with rotary automatic mechanism operated by the up and down motion of said housing and tool for automatically feeding screws to the screwdriver, movable up and down bodily with said motor, with fixed means on said table to operate said mechanism, said mechanism comprising a nozzle having yielding means to support the screw head in position to be engaged by the screwdriver, adapted to yield to permit passage of the screw out of the nozzle.

3. In apparatus for rotating a tool by power, the combination of a rotary member for supporting the tool in position to perform its desired work, a housing enclosing power controlling and transmission devices for rotating said member, a fixed table for the work, supporting and guiding instrumentalities mounted on said table at one side of said tool and whereby said housing is movable vertically to cause axial movement of said tool, means on said instrumentalities to adjust the housing and thereby move the tool up and down, said devices having means operable by said axial movement to open and close the mechanical transmission of power to said tool, and a motor rigid with said housing for operating said devices, movable up and down bodily therewith, said housing and motor being automatically movable upwardly in fixed relation, thereby to release the tool from the work and automatically open said transmission, said tool being a screwdriver, in combination with rotary automatic mechanism operated by the up and down motion of said housing and tool for automatically feeding screws to the screwdriver, movable up and down bodily with said motor, with fixed means on said table to operate said mechanism, said mechanism comprising a nozzle having yielding means to support the screw head in position to be engaged by the screwdriver, adapted to yield to permit passage of the screw out of the nozzle, said mechanism comprising hopper means and a guide leading from the hopper means to the nozzle, said guide having an escapement device for releasing the screws one by one, and means whereby said escapement device is operated by the axial movement of said motor and housing and tool.

4. In apparatus for rotating a tool by power, the combination of a rotary member for supporting the tool in position to perform its desired work, a housing enclosing power controlling and transmission devices for rotating said member, a fixed table for the work, supporting and guiding instrumentalities mounted on said table at one side of said tool and whereby said housing is movable vertically to cause axial movement of said tool, means on said instrumentalities to adjust the housing and thereby move the tool up and down, said devices having means operable by said axial movement to open and close the mechanical transmission of power to said tool, and a motor rigid with said housing for operating said devices, movable up and down bodily therewith, said housing and motor being automatically movable upwardly in fixed relation, thereby to release the tool from the work and automatically open said transmission, said tool being a screwdriver, in combination with rotary automatic mechanism operated by the up and down motion of said housing and tool for automatically feeding screws to the screwdriver, movable up and down bodily with said motor, with fixed means on said table to operate said mechanism, said mechanism comprising a nozzle having yielding means to support the screw head in position to be engaged by the screwdriver, adapted to yield to

permit passage of the screw out of the nozzle, said feed mechanism comprising a hopper provided with rotatable means, having guiding means by which the screws are swept by said rotatable means, and means whereby said rotatable means is operated by the axial movement of said housing and tool.

5. In apparatus for rotating a tool by power, the combination of a rotary member for supporting the tool in position to perform its desired work, a housing enclosing power controlling and transmission devices for rotating said member, a fixed table for the work, supporting and guiding instrumentalities mounted on said table at one 10 side of said tool and whereby said housing is movable vertically to cause axial movement of said tool, means on said instrumentalities to adjust the housing and thereby move the tool up and down, said devices having means operable by said 15 axial movement to open and close the mechanical transmission of power to said tool, and a motor rigid with said housing for operating said devices, movable up and down bodily therewith, said housing and motor being automatically 20 movable upwardly in fixed relation, thereby to release the tool from the work and automatically open said transmission, said tool being a screwdriver, in 25 combination with rotary automatic mechanism operated by the up and down motion of said housing and tool for automatically feeding screws to the screwdriver, movable up and down bodily with said motor, characterized by the fact that 30 said mechanism comprises a nozzle having yielding means to support the screw head in position to be engaged by the screwdriver, adapted to yield to permit passage of the screw out of the nozzle, said hopper means comprising a rotary cylinder, 35 a horizontal shaft, radial blades on the inner cylindrical surface of said cylinder, and a spring device for keying said cylinder to said shaft, adapted to permit quick removal of the cylinder from said shaft.

40

means comprising brushes operated back and forth about a horizontal axis, adapted to sweep the screws back and forth at the entrance to said guide, thereby to insure proper entry of the screws into said guide.

5

6. In apparatus for rotating a tool by power, the combination of a rotary member for supporting the tool in position to perform its desired work, a housing enclosing power controlling and transmission devices for rotating said member, a fixed table for the work, supporting and guiding instrumentalities mounted on said table at one side of said tool and whereby said housing is movable vertically to cause axial movement of said tool, means on said instrumentalities to adjust the housing and thereby move the tool up and down, said devices having means operable by said axial movement to open and close the mechanical transmission of power to said tool, and a motor rigid with said housing for operating said devices, 10 movable up and down bodily therewith, said housing and motor being automatically movable upwardly in fixed relation, thereby to release the tool from the work and automatically open said transmission, said tool being a screwdriver, in 15 combination with rotary automatic mechanism operated by the up and down motion of said housing and tool for automatically feeding screws to the screwdriver, movable up and down bodily with said motor, characterized by the fact that 20 said mechanism comprises a nozzle having yielding means to support the screw head in position to be engaged by the screwdriver, adapted to yield to permit passage of the screw out of the nozzle, said hopper means comprising a rotary cylinder, 25 a horizontal shaft, radial blades on the inner cylindrical surface of said cylinder, and a spring device for keying said cylinder to said shaft, adapted to permit quick removal of the cylinder from said shaft.
